HANGER FOR HANDBAGS AND THE LIKE

Albrecht von Schroeder, Denver, Colo.

Application March 12, 1935, Serial No. 10,672

2 Claims. (Cl. 248—214)

This invention relates to improvements in folding supports for handbags and the like.

Ladies ordinarily carry handbags of different sizes and when they go to a restaurant for meals, or sit down at a card table, the handbag must either be laid upon the table, or held in the lap, both ways of which are inconvenient. Since women usually carry money and other valuables in their handbags, it is necessary to keep them in view at all times, to prevent unauthorized persons from obtaining access to them.

It is the object of this invention to produce a hook or support of such construction that it can be readily carried in the handbag and which shall be so designed that it can be used for supporting the handbag from the edge of a table and which makes it possible for a woman to keep her handbag within sight and easy reach when seated at a table.

20 The improved support or hook that forms the subject of this invention will now be described in detail and for this purpose reference will be had to the accompanying drawing on which it has been illustrated in its preferred form and in which

25 Figure 1 is a fragmentary perspective view of a card table showing a handbag supported from the edge thereof by the improved hook;

Figure 2 is a section through the edge of the table, taken on line 2—2, Figure 1, and shows the 30 hook in place thereon, the handbag being indicated by dotted lines:

Figure 3 is a section taken on line 3—3, Figure 2, but shows only a portion of the hook; and

35 Figure 4 is an edge elevation of the hook showing the same in folded position and ready to be inserted into the handbag.

In the drawing, reference numeral 5 designates the top of a table, which in Figure 1 has been shown as an ordinary card table provided with 40 foldable legs 6. The hook 7 is formed from a wire or rod of any suitable material such as steel or brass, and whose surface may have any desirable finish such as nickel, silver or gold plating. The hook is so bent that it resembles, in a general 45 way, the letter S, the upper loop 8 being quite large in comparison with the lower loop 9, all as shown in Figure 2. The end 10 of loop 8 is directed downwardly and has its center in a plane x—x which passes through the center 11 of the loop 9. 50 End 10 is flattened and its sides lie in spaced planes perpendicular to the plane of the hook. End 10 is provided with an opening for the reception of the pivot pin 12. A plate 13, which may be either circular or oblong, is provided on its 55 upper surface with two lugs or ears 14 that are spaced to receive the end 10, and provided with openings for the reception of the pivot pin 12.

Plate 13 can be turned about pivot 12 from the 60 position shown in Figures 2 and 3 to the position shown in Figure 4; in the latter position the hook

can be said to be folded and can be easily put into the handbag or a pocket.

When the hook is to be employed for supporting a handbag or any other object, the plate 13 is turned from the position shown in Figure 4 to 5 that shown in Figures 2 and 3, and the hook is put into position over the edge of the table in the manner shown in Figures 1 and 2. The flat surface of the plate engages the table top and prevents it from becoming scratched or marred. The 10 under surface of the plate may have a covering 15 of rubber or felt if desired.

After the hook has been put into position, the handbag, designated by numeral 16, may be hung by its handle 17 from the loop 9. It will be seen 15 from the drawing that the hook can swing about the axis of the pivot 12, but not in the opposite direction. The handbag can be supported in either closed or open position, and when it is open, the owner has ready access to it at all times, which 20 is a great convenience.

After the hook has been used, it is removed and the plate 13 turned into the position shown in Figure 4, in which position it takes up very little space.

25 Although the hook is primarily intended to support handbags, it is evident that it can be employed for supporting any other articles such as clothing.

In the claims the words "upper" and "top" are 30 employed to designate the end of the hook having the enlarged loop and the "bottom" or "lower" the end having the small loop 9.

Having described the invention, what is claimed as new is:

35 1. A support comprising in combination, a hook-portion of substantially S-shape, the upper loop being larger than the lower and adapted to extend over the edge of a table top, the lower loop serving as a hook to support an object, the 40 end of the upper loop terminating in a portion whose axis extended intersects the lower loop, and a plate attached to the end of the upper loop by a pivot that is perpendicular to the axis and lies 45 in the plane of the hook-portion, said plate serving to contact with a supporting surface.

2. A support comprising in combination a hook-portion of substantially S-shape, the end of the upper loop being directed downwardly so that its 50 center line intersects the lower loop, the end of the upper loop having a plate attached thereto by a pivot pin that lies in the plane of the hook-portion and is perpendicular to the center line of the end of the loop, the plate being rotatable about 55 the pivot from a plane perpendicular to the center line and into a plane parallel with the plane of the hook-portion.
